UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,582, dated November 25, 1884.

Application filed October 1, 1884. Term of patent 3½ years.

To all whom it may concern:

Be it known that I, MARY TURNER, of the city, county, and State of New York, have invented and produced a new and original Design for a Pattern of a Lady's Costume, (numbered 9,497;) and I do hereby declare that the engraved prints accompanying this specification convey to any one accustomed to using paper patterns a clear understanding of how 10 a garment made up by the pattern will appear.

The design shows a round walking-skirt and an overdress. The skirt displays a front drapery that exhibits draping plaits high up at the left side, and falls about to the foot of the 15 skirt at the right side, where it appears to be folded over in a wide graduated revers. The overdress exhibits closely-fitted short basque-fronts that display a fastening all the way down, and lapel ornaments extending from

the shoulders to the bust; a deep polonaise-back that falls in straight folds to the lower edge of the skirt, and exhibits under-folded plaits at the lower ends of its middle three body-seams, and also in the top of its skirt near the front edges, where it appears to underlap the lower part of the short side backs; a standing collar, and coat-sleeves that exhibit gathers and a high roll at the shoulders.

What I claim as my invention, and desire to secure by Letters Patent, is—

The design for a lady's costume, as shown in the engraved prints accompanying this specification.

MARY TURNER.
